UNITED STATES PATENT OFFICE.

JACOB FELBEL, OF NEW YORK, N. Y., ASSIGNOR TO REMINGTON TYPEWRITER COMPANY, OF ILION, NEW YORK, A CORPORATION OF NEW YORK.

TYPEWRITING MACHINE.

Application filed June 2, 1924. Serial No. 717,209.

My invention relates to typewriting machines, and has for its object to provide a code system which is particularly adapted for use in connection with such machines. 5 More specifically my invention relates to the code system sometimes referred to as the "Russell" index. This system employs six basic consonants b, c, d, l, m and r some of which have a plurality of phonetic equivalents. Thus b stands not only for b but also represents or stands for f, p and v; c stands for e, g, j, k, s, x and z; d stands for d and t, l stands for itself alone; m stands for m and n; and r stands for itself alone. For 10 this system the vowels are disregarded as well as the consonants y, w and h. These key consonants may be grouped in desired combinations, thus greatly simplifying index systems based primarily on the usual 15 alphabetical principle. In the present system heretofore it has been the custom to memorize the key letters and their equivalents. My improvements consist in distinguishing all of the key letters or characters 20 of the code system by the same mark or characteristic, such as a star, a period or the like, thus providing an automatic checking or designating of such code letters or characters as they are written, and obviating the 25 necessity of the operator memorizing the key letters or checking them by hand at a separate operation, as has heretofore been the practice.

To the above and other ends which will 30 hereinafter appear, my invention consists in the features of construction, combinations of devices, and arrangements of parts herein- 35 after described and particularly pointed out in the claims.

One form of my invention is illustrated in 40 the accompanying drawings wherein,

Figure 1 is a fragmentary plan view of a set or series of type bars embodying my invention, the type blocks on the ends of the 45 type bars being shown as they lie in the basket.

Figure 2 is a standard Remington key- 50 board as modified for use with my invention.

Figure 3 illustrates various spellings of 55 a name with code letters indicated.

Figure 4 is a fragmentary view of several type bars and their type blocks drawn to an enlarged scale.

In the index system to which I have 55 adapted my invention, the key letters com-

prise lower case f, p, v, in one group; c, g, j, k, q, s, x and z in a second group; d and t in a third group; l by itself; m and n in a fifth group; and r by itself. These different groups are separately distinguished 60 according to the code system aforesaid, but for the purposes of my invention I designate all of the characters of all of the groups by the same mark or indicating sign, preferably, as shown herein, a star or asterisk. Referring to Figures 1 and 4 of the drawing, 65 each type bar 1 carries a type block 2 which is provided with an upper case character 3 and a lower case character 4. I have not shown in Figure 1 all of the characters on 70 the type blocks but have only shown the code characters, all of the code characters being lower case letters and arranged at the rear end portions of the type blocks. Associated with each of these code letters is a 75 star designated as 5, the star being the preferred device for distinguishing or designating the code characters. These stars 5 are so related to their associate letters that they will print simultaneously therewith and 80 slightly above and at the right-hand side of their letters, resulting in a line of stars distinct from the line of letters. Referring to Figure 2, wherein the key caps or buttons 85 of the standard keyboard are designated as 6, it will be observed that I have provided the keys of all of the code letters with the distinguishing mark or star. This gives visual indication of the full set of code character keys.

In Figure 3, I have illustrated the variants 90 of a single name as follows: "Farnam", "Farnum" and "Farnham", as they appear 95 when printed by a typewriting machine embodying my invention. It will be observed that the key or code letters are the same in each instance, namely r, m and n, and that these key letters are visually indicated or distinguished by stars, the stars appearing 100 in a line above the key letters and so that these letters may readily be noted at a glance. This helps to bring out certain of the advantages of my invention, namely, the operator is not put to any mental effort to 105 remember the key characters, the liability of error is done away with, and the key characters are automatically checked by a uniform mark, thus saving the operator 110 from doing this with a pencil or otherwise.

11. A device of the character described, expanding said blades beyond, and with-
including a tubular driving stem having an internal annular shoulder forming a seat, near its lower end, a blade carrier movable through said stem, and having an external annular shoulder adapted to rest on said seat to support said carrier, expandible blades carried by said carrier, and means for drawing them within said carrier, said 10 means including a wedge like web which works between said blades.

In testimony whereof I have signed my name to this specification.

REDUS D. DODDS.
